UNITED STATES PATENT OFFICE.

HENRY PETERSON, OF DUNKIRK, MONTANA.

SADIRON.

1,377,971.

Specification of Letters Patent.

Patented May 10, 1921.

Application filed May 1, 1920. Serial No. 378,091.

To all whom it may concern:

Be it known that I, HENRY PETERSON, a citizen of the United States of America, residing at Dunkirk, in the county of Toole 5 and State of Montana, have invented new and useful Improvements in Sadirons, of which the following is a specification.

The object of the invention is to provide simple and efficient means whereby an operating handle may be readily connected with and disconnected from a sad iron to permit the interchangeability of the former to the end that the handle may be constructed of or include heat non-conducting material for the purpose of protecting the hand of the operator, and thus not subjected to the temperature of the means employed for heating the body of the iron, and with these objects in view the invention consists in a construction and combination of parts of 20 which a preferred embodiment is shown in the drawing, wherein:

Figure 1 is a side view of the device.

Fig. 2 is a horizontal section on the plane indicated by the line 2—2 of Fig. 1.

Fig. 3 is an end view.

Fig. 4 is a vertical section on the plane indicated by the line 4—4 of Fig. 1.

Fig. 5 is a detail section on the plane indicated by the line 5—5 of Fig. 2.

The sad iron body 10 which may be of any material suitable for the purpose, is provided with a seat 11 formed by the space between parallel bars or ribs 12 formed upon 35 or secured to the upper surface of the body, an upstanding tongue 13 being arranged, for example, about midway of the length of the seat and having a transverse bolt opening 14 for engagement by a bolt 15 carried by the 40 handle 16 when the latter is in operative relation with the body of the iron. The handle in addition to the grip portion 17 and suitable standards 18 includes a base bar 19 adapted to fit in the seat 11 formed longitudinally of the upper side of the iron body, and the bolt 15 which is provided with a 45 coiled actuating spring 20 is mounted at its forward end in guides 21 and 22 carried by said base bar and spaced apart at an interval sufficient to permit of the arrangement 50 of the tongue 13 therebetween.

At its outer end the bolt is also mounted in a guide 23 in one of the standards 18 and is provided with a collar 24 in engagement with which is arranged an operating lever 55 25 fulcrumed as at 26 upon the standard and having a finger-hold 27 arranged within convenient reach of the thumb or forefinger of the hand grasping the grip 17. The tendency of the actuating spring 20 by pressure against a collar 28 on the locking bolt is to advance the latter and yieldingly hold the same in engagement with the socket or opening in the tongue 13, and when it is desired to either attach or detach the handle 60 it is necessary to press the finger-hold 27 to move the locking bolt in opposition to its actuating spring so as to withdraw the engaging end of the bolt from the plane of the tongue 13. When engagement of the 70 handle with an iron is to be effected the bolt may be withdrawn as indicated and the base bar fitted into the seat 11 so as to engage an opening 23^a in the base bar with the tongue whereupon the release of the finger-hold 75 will permit the bolt to advance and engage both the tongue and the guide 22 and thus lock the handle and iron body together to permit of the usual operation of the latter. Obviously to detach the handle from the iron 80 body it is simply necessary to reverse the operation by first disengaging the locking bolt by pressure upon the finger-hold 27.

What is claimed is:

A sad iron having a body provided with 85 a longitudinal seat and an upstanding tongue, a handle having a base bar for engagement with said seat and provided at an intermediate point with an opening for the reception of said tongue, a spring-actuated bolt provided with a collar and mounted upon the base bar for engagement with an opening in the tongue, and a bolt-operating lever mounted upon the handle in engagement with the collar on the bolt and provided with a finger-hold disposed adjacent to one end of the handle grip. 90 95

In testimony whereof I affix my signature.

HENRY PETERSON.
